His Attorney.

UNITED STATES PATENT OFFICE

2,345,375

ELECTRIC CIRCUIT BREAKER

Robert M. Bennett, Ithan, Pa., assignor to General Electric Company, a corporation of New York

Application December 19, 1942, Serial No. 469,519

4 Claims. (Cl. 200—148)

My invention relates to electric circuit breakers, more particularly to circuit breakers of the gas blast type wherein a blast of arc extinguishing gas such as air under pressure is directed into the arc gap formed upon separation of the breaker contacts, and has for its principal object the provision of an improved circuit breaker of the aforesaid type that is more efficient in its cooling treatment and disposal of the interrupting blast gases that are vented from the breaker for preventing ejection of flame therefrom.

In a successful and well-known type of air blast circuit breaker, the air blast is directed substantially transversely of the arc to drive the arc into insulating arc chute structure where it is extinguished. In this design, the arc is drawn across a plurality of insulating arc barriers forming exhaust passages in the chute and the gas blast is applied at the opposite side to drive the arc against the barriers and into the passages. In this form of cross blast breaker a movable blade contact coats with a fixed contact opposite the insulating arc barrier edges so that the exhaust passages are uncovered in sequence, the first passage to be uncovered being the farthest from the chute's main exhaust passage. Accordingly, the passage last to be uncovered, which is nearest the main exhaust is adapted when the arc is interrupted early in its formation to direct comparatively cool unheated blast air into the highly heated gases that are vented from the first passage or passages so as to mingle with and cool said gases. Also since the exhaust gases often contain combustible gases, the fresh air blast supplies oxygen for aiding complete combustion before final venting, thereby tending to eliminate flame-throw from the breaker.

In accordance with my invention, the ejection of flame from the breaker is greatly minimized by means for both cooling the gases by heat transfer to metallic surfaces and for creating a high degree of turbulence and centrifugal action in the main exhaust passage including vanes or the like arranged to direct the blast gases toward the exhaust along a helical path or a series of helical paths.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view in section illustrating a cross-blast air circuit breaker embodying my invention in the

open circuit position thereof, and Fig. 2 is a sectional view taken along the line 2—2 of Fig. 1.

The cross-blast type air circuit breaker shown by way of example in Fig. 1 comprises relatively movable arcing contacts, such as fixed contact structure 1 of the "finger" type and a reciprocally guided blade-like contact 2. The fixed contact is electrically connected as indicated to one line terminal of the breaker at 3 and the blade-like movable contact is also indicated as connected to the other line terminal at 4. The blade contact 2 is movable by suitable actuating means (not shown) along a generally rectilinear path to make and break the circuit with respect to the fixed contact 1.

For the purpose of extinguishing the arc formed between the contacts when a power circuit is opened, an insulating arc chute 5 is arranged with respect to the contacts so that the arc is drawn at the entrance of the chute directly opposite a gas blast supply conduit 6. The conduit 6 is suitably connected through a blast control valve (not shown) to a source of compressed gas, such as air, comprising for example a storage tank and compressor equipment (not shown).

The arc chute 5 defines a narrow, diverging space into which the arc is driven and extinguished by the blast and is formed by diverging end walls 7 and 8 and comparatively closely spaced parallel side walls, one of which is shown at 9, connected to a bottom wall 10 through which the blast passage extends. The walls of the chute are composed of a mechanically strong insulating material, such as a molded laminated structure. The exhaust end of the chute is closed except for a laterally extending conduit or stack 11 which directs the heated blast gases away from the circuit breaker proper. The conduit 11 forms the main exhaust passage for venting the blast gases from the breaker proper.

The chute also includes a plurality of insulating arc barriers 12 and 13 that are disposed edge-wise to the arc path with the barrier width transversely of the arc path so as to form diverging gas passages in which are spaced metal cooling plates 14 leading to the exhaust conduit. The barriers extend fairly close to the arc path as indicated and are composed of a vaporizable insulating material such as hard fibre that does not lose its insulating characteristics in the presence of the arc. The insulating material does however give off highly heated gases in vaporizing that produce flame when united with air or oxygen. This may be explained as follows: The exhaust gas in the breaker contains unburned car-

bon, hydrogen, carbon monoxide, and solid carbon particles which come from the destruction of the insulating parts of the circuit breaker, and in addition, particles of copper and tungsten from the contacts. The gases may be sufficiently cool to fail to burn upon being mixed with fresh air, but either spontaneous combustion of the carbon particles or ignition by incandescent solid particles of copper and carbon often causes burning of the gas. This is the flame that is often ejected during the interruption of heavy power currents.

A circuit breaker of this character is disclosed and claimed in Prince et al. Patent No. 2,284,842, issued June 2, 1942, for "Circuit breaking apparatus" and assigned to the same assignee as the present invention.

The arc chamber or space in which the arc is drawn is formed at the entrance of the chute between the blast supply conduit 6 and the arc barriers 12 and 13 and constitutes an elongated chamber 15 having at one end an opening 16 in registry with the movable contact 2 which can move exteriorly of the chute to a safe isolating distance. The barrier 13a extends entirely across the arc chamber for confining the arc flame to the chute interior and has a slot 13b also in registry with the contact 2. The arc formed between the separated contacts may extend longitudinally of the chamber as is evident from Fig. 1 so as to be in the direct path of the gas blast as it is directed into the chute. The arcing is preferably confined to special arcing portions or tips 1' and 2' on the fixed and movable contacts respectively.

It will therefore be noted that the arc gap initially is formed adjacent to and across the entrance to the first exhaust passage 12' defined by the barrier 12 and the arc chute end wall 8. This passage is farthest from the exhaust conduit 11. The movable contact, as it is withdrawn from the chute uncovers the other exhaust passages in succession which are progressively nearer said conduit. The arc chute end at the blast exhaust conduit forms in effect a mixing chamber 13c for the exhaust gases. In this arrangement the blade contact moves from the fixed contact so as to open the first passage at 12' so that the initially formed arc can be looped by the blast against the edge of the first barrier 12. The arc is often interrupted at the first arc barrier. In such a case fresh blast air, for example, enters the chamber 13c from the later uncovered passages before complete venting of the highly heated and partly combustible arc gases and mixing of these gases with air therefore takes place within this chamber. However, this mixing in itself is often inadequate to prevent flame ejection from the breaker.

There are a number of factors involved in flame ejection or "throw" from the breaker. For example, if the gases are sufficiently cooled and no igniting means, such as incandescent particles are present, there may be no flame even though combustible gases are vented with other exhaust gases. Also, if complete combustion takes place within the breaker and exhaust passages before venting there will be no flame. In accordance with my invention, the exhaust gases are cooled, thoroughly intermixed by turbulent flow to bring about more complete combustion and also subjected to centrifugal action for separating out solid incandescent particles, such as metal, carbon, etc.

In a specific form of my invention shown by Fig. 1, the exhaust conduit 11 is provided with

a plurality of stationary metal vane structures 17 of fan-like form. Each vane structure 17 as shown by Fig. 2 comprises blades 17' having a suitable pitch for imparting a positive helical motion or whirl to the exhaust gases. The vane structures 17 are also sufficiently spaced within the exhaust passages to form in effect a series of combustion and separating chambers for both burning the gases and separating out solid particles. It will be apparent that due to the high linear velocity of the exhaust gases through conduit 11, there will be set up by the whirling motion indicated in Fig. 1 positive centrifugal forces tending to throw solid incandescent particles to the conduit walls where they are precipitated instead of being expelled with the arc gases. Accordingly, the possibility of igniting any combustible gases that escape complete burning within the breaker is greatly reduced.

Although I have shown the pitch of the blades 17' substantially uniform it will be apparent that they can be varied to any suitable degree. Also, the pitch of the blades of certain vane structures can be reversed so that, for example, the gases 25 are whirled clockwise in one chamber, such as 18, and relatively counterclockwise in an adjacent chamber as 19. This would produce greater turbulence due to the rapid reversal of gas flow while retaining the centrifugal action. Since the 30 vanes 17 are preferably composed of a suitable metal having good heat conductivity the gases are also cooled by contact with the blade surfaces.

It should be understood that my invention is not limited to specific details of construction and arrangement thereof herein illustrated, and that changes and modifications may occur to one skilled in the art without departing from the spirit of my invention.

40 What I claim as new and desire to secure by Letters Patent of the United States is:

1. An electric circuit breaker of the gas blast type comprising an arc extinguishing chamber, said chamber including vaporizable insulating structure, means including a gas blast for interrupting the arc formed upon opening of the circuit within said chamber, an exhaust passage for venting the blast gases from said chamber, said gases including combustible gases and carbon and metal particles from said chamber, and means disposed in said exhaust passage for imparting to said gases a whirling motion progressing toward the exhaust end of said passage so that turbulence of said gases is promoted within 55 said passage and solid particles in said gases are precipitated to the passage walls by centrifugal action thereby minimizing flame at the atmospheric exhaust of said passage.

2. An electric circuit breaker of the gas blast 60 type comprising an arc extinguishing chamber, means including a gas blast for interrupting the arc formed upon opening of the circuit within said chamber, an exhaust passage for venting the blast gases from said chamber to atmosphere, and means including vane structure disposed in said exhaust passage at spaced intervals for causing said gases to flow along a generally helical path leading to the exhaust of said passage so that turbulence of said gases is promoted within said 70 passage and solid particles in said gases are precipitated to the passage walls by centrifugal action.

3. An electric circuit breaker of the gas blast type comprising an arc extinguishing chamber, means including a gas blast for interrupting the

arc formed upon opening of the circuit within said chamber, an exhaust passage for venting the blast gases from said chamber, and a plurality of relatively fixed vanes disposed in said exhaust passage at spaced intervals, said vanes being positioned with respect to the linear flow of said gases for imparting to said gases a whirling motion leading to the exhaust of said passage so that solid incandescent particles in said gases are precipitated to the passage walls by centrifugal action thereby to minimize flame when the gases are finally vented to atmosphere.

4. An electric circuit breaker of the gas blast type comprising an arc extinguishing chamber,

means including a gas blast for interrupting the arc formed upon opening of the circuit within said chamber, an exhaust passage for venting the blast gases from said chamber, and a plurality of fan-like structures disposed in spaced relation in said exhaust passage, said fan-like structures having blades pitched with respect to the linear flow of said gases through said passages for imparting to said gases a whirling motion so that turbulence of said gases is promoted within said passage for aiding combustion and solid incandescent particles in said gases are precipitated to the passage walls by centrifugal action.

ROBERT M. BENNETT.
